UNITED STATES PATENT OFFICE.

JOHN H. FOX, OF CLEVELAND, OHIO, ASSIGNOR TO GEORGE M. POTTER,
OF CLEVELAND, OHIO.

REPEATING TORPEDO-CANE.

SPECIFICATION forming part of Letters Patent No. 773,635, dated November 1, 1904.

Application filed December 21, 1903, Serial No. 185,920. (No model.)

To all whom it may concern:

Be it known that I, JOHN H. FOX, a citizen of the United States, residing at Cleveland, in the county of Cuyahoga and State of Ohio, 5 have invented certain new and useful Improvements in Repeating Torpedo-Canes; and I do declare that the following is a full, clear, and exact description of the invention, which will enable others skilled in the art to which it applies to make and use the same.

My invention relates to repeating torpedo-canes; and the invention consists in the construction and combination of parts substantially as shown and described, and particularly pointed out in the claims.

In the accompanying drawings, Figure 1 is a vertical sectional elevation of my new and improved cane; and Fig. 2 is a plain elevation thereof, the handle being broken off in both 20 views. Fig. 3 is a cross-section on a line corresponding to xx , Fig. 1; and Fig. 4 is a plain elevation of the plunger and a section of the handle socketed therein.

In the drawings, the part A represents an 25 explosion-head or head having an explosion-chamber in its lower portion and in which the bottom 2 of the head is closed and constitutes an anvil upon which the torpedo is struck by the plunger, and one or more exhaust-openings 3 are provided just over this bottom to discharge the products of the explosion. The 30 said head is preferably a cast member—say of malleable iron or other metal of a suitable quality—and is further characterized by a tubular magazine 4, projecting outwardly and upwardly at its top into a plane parallel to the handle B and fairly close thereto and of such size or length as to contain a charge of torpedoes 5 and more or fewer according to 35 size. Directly beneath this extension there is a side space 6 or space out of line with the plunger provided with a vent-opening 7 in or near its top adapted to prevent possible back-firing from the explosion-chamber to the magazine. The side space 6 has an inclined lower 40 surface upon which the cartridges roll or slide promptly into the explosion-chamber as they are liberated one by one from above, and the said inclined surface terminates a sufficient

distance above the bottom of head A to produce a comparatively close-fitting chamber for plunger C beneath the same when the blow occurs.

Now in order that the cartridges shall be fed to the explosion-chamber one at a time 55 and regularly with each explosion I provide the plunger with a cavity 8 in its side directly opposite the mouth of the magazine and in such relation thereto and of such size as to receive a single cartridge and no more 60 each time the plunger is raised to its upward limit, while the plunger has its discharge from said cavity into the side space 6 when it reaches its downward limit of thrust, as seen in dotted lines, Fig. 1. In other words, 65 the instant an explosion occurs another cartridge is dropped into the side space 6 ready to pass into the explosion-chamber upon the raising of plunger C, and when the plunger is raised it at once receives another cartridge 70 in cavity 8. Thus two cartridges are delivered, one for explosion and one in the plunger-cavity, and this is continuous and unending as long as a charge of cartridges lasts. Thus I am enabled to keep up as rapid firing 75 as it is physically possible to operate the plunger, a rate which is so quick as to quite blend the sound of the explosions. This rapid firing and the consequent intense heat generated makes the vent 7 of very material importance, 80 for otherwise there would be constant danger of back-firing into the magazine and possible accident on that account.

The handle is socketed in plunger C, and 85 said plunger is confined upon and within head A and in a sliding relation thereto by means of a screw 9, engaged in the plunger, through a lengthwise slot 10 in the head.

The drawings as filed herewith represent the 90 device in full size.

From the foregoing description the operation of the cane is obvious. For all practical purposes the head A might be fixed or stationary and the plunger reciprocated therein. Each downward stroke of the plunger both 95 causes an explosion and carries down another torpedo, which drops into the explosion-chamber the instant the plunger is raised to repeat

a blow. As this occurs the cavity or pocket in the plunger receives another torpedo from the magazine, and so on. The feed of the torpedoes goes on automatically from cavity 8 5 in the cane through side space 6, as already described.

What I claim is—

1. The combination of the plunger having a cartridge-receiving cavity in its side and a handle to operate the plunger, with the head 10 slidably suspended from the plunger and provided with a cartridge-receiving extension at its top in a plane outside said plunger and with the mouth thereof in position to register 15 with the cavity in the plunger, and a side space in the head having a vent-opening and in position to direct the cartridges into the explosion-chamber, substantially as described.
2. In torpedo-canè, a head for the cane provided with an explosion-chamber in its bottom and a magazine extension at its top outside the plane of the head and a side space for transferring the cartridges from the magazine to said chamber, in combination with the 25 plunger provided with a cavity to transfer the torpedoes from the magazine to said side space, substantially as described.

3. In a repeating torpedo-canè, a head having an explosion-chamber and a cartridge-magazine integral with the upper portion 30 thereof and outside its axis, in combination with a plunger slidably engaged in said head and provided with a cavity in its side to register with the bottom of the said magazine, the said head having at its side beneath the 35 magazine a side space to deliver the torpedoes into the explosion-chamber, substantially as described.

4. In torpedo-canè, a head provided with an explosion-chamber and a magazine integral 40 therewith outside the axis of said chamber, and a plunger slidably engaged with said head and constructed with a space to receive and transfer one torpedo at a time from said magazine to the explosion-chamber, and a handle secured to said plunger, substantially as described. 45

In testimony whereof I sign this specification in the presence of two witnesses.

JOHN H. FOX.
